C. K. VOLCKENING

CASING FOR RADIATORS AND HUMIDIFIERS

Filed Dec. 15, 1925

UNITED STATES PATENT OFFICE.

CHARLES KASPER VOLCKENING, OF BROOKLYN, NEW YORK, ASSIGNOR TO GEORGE GOULD BERRY, OF BROOKLYN, NEW YORK.

CASING FOR RADIATORS AND HUMIDIFIERS.

Application filed December 15, 1925. Serial No. 75,579.

My invention relates to casings for radiators and humidifiers.

More particularly stated, my invention comprehends an improved casing and an 5 improved water pan connected therewith.

Reference is made to the accompanying drawing forming a part of this specification, and in which like reference characters indicate like parts throughout the several 10 figures.

Figure 1 is a side view, partly an elevation and partly a section, showing my invention.

Figure 2 is a plan view of the device, 15 partly broken away.

Figure 3 is a section on the line 3—3 of Figure 2, looking in the direction indicated by the arrows.

Figure 4 is an end elevation of my de- 20 vice.

Figure 5 is an enlarged fragmentary section on the line 5—5 of Figure 2, looking in the direction indicated by the arrows.

A radiator is shown at 5, and is provided 25 with a pipe 6 and a hand valve 7, these parts being of the usual or any preferred construction.

Resting upon the radiator 5 is my im- 30 proved water pan 8, used for humidifying or moistening the air, as heated and circu- lated by the radiator. The water pan con- tains a volume of water 9, which gradually evaporates and is replaced from time to time, as hereinafter described.

In the construction of my improved ra- 35 diator casing I provide a pair of end plates 10 and 11 and a pair of side plates 12 and 13, each plate provided with perforations 14 to facilitate the passage of air through 40 the casing.

The end plates are each provided with a 45 number of corner eyes 15, and the side plates are each provided with corner eyes 16. The corner eyes carried by each plate are spaced apart, and so aligned relatively to each other that when the plates are fitted together, as indicated in Figure 2, the eyes carried by each end plate are brought into dovetail engagement with the eyes of the 50 side plates, somewhat after the manner in which the eyes of different portions of an ordinary two-part door hinge are inter- fitted.

For the purpose of holding the plates together when their eyes are thus brought into alinement, I provide corner rods 17. These corner rods, four in number, are simply threaded vertically downward through the eyes at the four corners of the casing as indicated in Figure 4.

The radiator casing is provided with a top plate 18, having eyes 19 similar to the eyes already described, and co-related to other eyes 20, with which the side plates 12 and 13 are provided.

The end plates 10 and 11 are each provided with a slot 21 for accommodating the water pan 8, as hereinafter more fully explained.

The end plate 11 is provided with a slot 70 22, to facilitate placing this end plate down over the pipe 6, as indicated in Figure 4.

I provide two corner rods 23, which are threaded through the eyes 19 and 20 above described, and are thus used for connecting 75 the top plate 18 with the side plates, and which normally extend horizontally.

I provide four guide rods 24, 25, 26, 27, which extend through the casing in the direction of the length thereof, and thus when 80 in position are normally horizontal, and parallel with each other. These guide rods are held in position by the aid of nuts 28, detachably mounted upon the ends thereof, as indicated more particularly in Figure 2.

My improved dust-catching screen is made in three sections 29, 30 and 31, each 85 made of material through which air can pass freely, but through which particles of dust and smoke do not pass, so that as the air circulates through the radiator casing, the 90 particles of dust and smoke are arrested and held upon the surface or within the substance of the material. As the material here contemplated I may employ cloth or other 95 textile fabrics of various kinds, but I preferably use loosely woven cloth made of wool, cotton, hemp, jute or other vegetable fiber, or screening cloth of wire or metal gauze, or in fact I may employ almost any sort of material which will arrest and hold particles of dust while allowing the air to pass through. The material is preferably flexible and of small mesh or of sleazy texture. Cotton flannel may be used if of such texture 100 that the air can get through it freely. How-

ever, I do not limit myself to the use of any particular material for the dust-catching screen.

The section 29 is rectangular in its general form, and extends over and is supported by the four guide rods 24, 25, 26, 27. The ends are provided with snap fastening members 32 which are mated by other snap fastening members 33, the latter being mounted rigidly upon the lower edges 34 of the side plates. That is to say, the ends of the dust-catching screen 29 are detachably connected with the lower edges of the side plates by means of fastenings which are of the general type used as snap fastenings for gloves.

The lower edges 34 of the side plates of the radiator are bent slightly inward, as indicated at the bottom of Figure 3. Similarly the lower edges 35 of the end plates are bent inwardly.

The sections 30 and 31 are simply towel-like members of the screening material above described. The sections 30 and 31 are alike, and each at its upper end is secured by snap fastenings 36 to any convenient part of the casing frame, and at its bottom end it is secured by fastenings 37 to the lower edge 35 of the adjacent end plate 10 or 11. Guide rods 38 serve to further hold the screen sections 30 and 31. However, the guide rods 38 are not essential, and may be omitted.

Each section 29, 30 and 31 of the dust-catching screen gradually becomes soiled as it gathers dust. At intervals the fastenings 35 are disconnected, the screen section removed, and cleansed thoroughly by washing or by the use of a vacuum cleaner. This done, the screen sections are replaced. Of course more than one screen section of the same kind can be employed, one being left in use while another is being cleaned.

The water pan 9 is provided with a central opening 39 extending entirely through it in a vertical direction. This opening extends nearly the full length of the radiator casing, as may be understood from Figure 2. The purpose of the opening 39 is to permit the air, heated by the radiator, to pass upwardly into the top portion of the casing. This air passes through the adjacent portion of the screen section 29, and through perforations 40 in the top plate 18. Meanwhile, other portions of the heated air pass through other portions of the screen section 29 and also through the other screen sections 30 and 31, and out through the perforations 14.

I find it advantageous to allow a portion of the vapor from the water pan to pass through the screen. For this purpose I provide the water pan with a series of upwardly projecting domes 43, in two rows each extending nearly the entire length of the casing, these domes being provided with vapor

holes 44. Except for these vapor holes, the top of the pan, so far as housed within the casing, is closed. The vapor escaping through the vapor holes is mixed with the air circulating through the casing, and thus humidifies the air. At the same time, the vapor is more or less instrumental in causing the dust to adhere to the dust-catching screen.

In order to prevent overheating of the water pan, and particularly to prevent the water from boiling, I provide a pair of blocks 45, made of asbestos or other heat-insulating material, and also make provision for detachably supporting these blocks in position underneath the water pan. The blocks 45 are of such size and form, and when in normal position so spaced apart, as not to obstruct the central opening 39. The water pan 8 is provided with downwardly projecting flanges 46, 47, so formed as to constitute slideways, and the asbestos blocks are slidably and thus detachably fitted into these slideways. One or both of the asbestos blocks may be used at a time, as they are each removable and replaceable independently of the other.

The water pan is provided with curved end portions 41, and with gratings 42 carried by these portions. As the water 9 gradually dries out or passes off in the form of vapor, it is replenished by removing the gratings, and pouring water into the pan.

As may be understood from the foregoing description the two side plates and the two end plates are easily connected together and held by the corner rods 17. By withdrawing these rods the end plates and side plates come apart. Similarly the side plates and the top plate 18 are connected together and held in position by the rods 23, and are disconnected by simply pulling out these rods.

To remove the end plates 10 and 11, they are simply swung outwardly at the bottom and moved angularly upward to disconnect them from the curved portions 41 of the water pan. To replace them, the slots 21 are moved angularly downward over the curved ends 41 of the water pan, so that the end plates 10 and 11 are brought into the positions indicated for them in Figure 1.

The operation of my device may be understood from the foregoing description.

The various parts of the radiator casing being formed and assembled as above described, and the various other parts being likewise in position, the radiator heats the air immediately around it and causes this air to pass through the dust-catching screen and through the perforations in the side plates, the dust from this air being arrested and held by the dust-catching screen as above described.

The various parts of the radiator casing, together with the water pan and the dust-

catching screen, may be grouped together in very compact form, and as thus grouped together can be shipped and handled with a minimum of time and at relatively small expense.

The various parts are of such form as to enable them to be readily standardized.

I do not limit myself to the precise apparatus shown, as variations may be made therein without departing from my invention, the scope of which is commensurate with my claims.

I claim—

1. The combination of a radiator casing 15 provided with end plates having slots, and a water pan housed within said radiator casing and provided with portions extending through said slots and bent upwardly.

2. The combination of a radiator casing 20 provided with slots, and a water pan housed within said radiator casing and provided with end portions extending outwardly through said slots and bent upwardly, said end portions being open to facilitate the 25 escape of moisture and to facilitate the replenishing water contained in the pan.

3. A device of the character described, comprising a radiator casing provided with slots, a water pan housed within said casing 30 and provided with portions extending through said slots and upwardly therefrom,

said water pan being provided with vapor holes located within the casing for humidifying air therein.

4. A device of the character described, 35 comprising a radiator casing and a water pan housed within said radiator casing, and a member having low heat conductivity and detachably connected with the bottom of said water pan, to prevent said water pan 40 and its contents from becoming overheated.

5. A device of the character described, comprising a water pan provided with projecting flanges, blocks of heat insulating 45 material engaging said flanges for preventing the water in said pan from boiling, and means for discharging vapor from the water in said pan into said casing.

6. A device of the character described, comprising a casing for enclosing a radiator, 50 and a water pan located within said casing for the purpose of being heated by said radiator, said water pan being provided with an open passage extending vertically through it in order to permit air to circulate through 55 said water pan, and also provided with a covering having holes to permit the discharge of vapor within said casing.

Signed at New York city, in the county of New York and State of New York, this 14th 60 day of December, 1925.

CHARLES KASPER VOLCKENING.
